J. L. HAMILTON.
ORCHARD HEATER.
APPLICATION FILED OCT. 31, 1913.

1,092,835.

Patented Apr. 14, 1914.

FIG. 1

FIG. 2

UNITED STATES PATENT OFFICE.

JAMES L. HAMILTON, OF GRAND JUNCTION, COLORADO, ASSIGNOR TO HAMILTON
ORCHARD HEATER COMPANY, OF WHEELING, WEST VIRGINIA, A CORPORATION
OF WEST VIRGINIA.

ORCHARD-HEATER.

1,092,835.

Specification of Letters Patent. Patented Apr. 14, 1914.

Application filed October 31, 1913. Serial No. 798,427.

To all whom it may concern:

Be it known that I, JAMES L. HAMILTON, a citizen of the United States of America, and resident of Grand Junction, county of Mesa, 5 and State of Colorado, have invented certain new and useful Improvements in Orchard-Heaters, of which the following is a specification.

This invention relates broadly to orchard heaters, and specifically to a draft controlling device for such heaters.

The primary object of the invention is to provide, in an orchard heater of the oil burning type, means whereby a regulatable 15 air supply may be admitted to the stack for facilitating the combustion within said stack of gases generated within the fuel receptacle or reservoir which communicates with said stack.

20 A further object is to provide in connection with an apparatus of the character mentioned means for regulating the air supply to the fuel receptacle for mixing with the gases prior to their entrance to the stack. 25 And a still further object is to provide means for thoroughly commingling air with the gases before the combustion point is reached in order to produce a highly efficient combustible mixture.

30 With these and other objects in view, the invention resides in the features of construction, arrangements of parts and combinations of elements which will hereinafter be exemplified, reference being had to the accompanying drawings, forming a part of 35 this specification, in which—

Figure 1 is a central vertical section of an orchard heater cover and stack, illustrating a preferred embodiment of my invention; 40 and Fig. 2 is a similar view showing a modification.

Referring to said drawings in which like designating characters distinguish like parts throughout the several views—1 indicates a 45 cover for the fuel reservoir of an orchard heater of a common oil burning type, said cover having provided therein the usual opening through which communication is had with a superposed stack. Having its 50 lower and larger end suitably attached to

said cover about said opening is a short frusto-conical stack 2, hereinafter termed the inner stack. Disposed in concentric encircling relation to said inner stack is a second stack 3, hereinafter termed the outer stack, 55 the same being of greater length than said inner stack. The outer stack is preferably of frusto-conical shape and is mounted with its smaller end lowermost, as shown.

Referring specifically to Fig. 1, there is 60 interposed between the inner stack and the outer stack a sleeve 4 which more or less closely embraces and is rotatable with respect to said inner stack. The lower end of the outer stack seats upon said sleeve near 65 the lower end of and is rotatable with the latter. Due to the fact that the outer stack and the sleeve 4 are tapered in opposite directions, they diverge upward one from the other from their point of engagement near 70 the lower end of the sleeve, as shown. Formed in said outer stack at a suitable point is an inwardly directed annular crimp 5 which embracingly engages the sleeve near 75 the upper end of the latter. Thus there is formed between the outer stack and said sleeve an annular chamber 6 to which air is freely admitted through a plurality of openings or perforations 7 provided in said stack. 80

Provided respectively in the inner stack 2 and the sleeve 4 are perforations 8 and 9, those of the latter being adapted to be carried into and out of registration with those of the former by rotation of said sleeve, accomplished in any appropriate manner, as by applying slight power to a lever 10 mounted upon said sleeve below the lower end of the outer stack 3. Thus, by adjustment of said sleeve the volume of air admitted to the inner stack from the chamber 6 through the perforations 8 and 9 is regulated. Referring now to Fig. 2, it will be observed that the positions of the outer stack and the sleeve with respect to each other are reversed, the stack 3^a having its lower end seated in embracing engagement with the inner stack near the lower end of the latter, having its crimp 5^a embracingly engaging the inner stack, and the sleeve 4^a 100

2
being disposed in embracing relation to the lower end of, and rotatable with respect to, said outer stack. Provided respectively in said sleeve and outer stack are perforations 5 11 and 12, those of the former being adapted to be carried into and out of registration with those of the latter by rotation of said sleeve, for regulating the volume of air admitted to the chamber 6^a. From said chamber, the air freely passes to the interior of the inner stack through perforations 13 provided in the latter. An annular outwardly directed flange 14 is formed on the lower end of the sleeve, the same resting upon the 10 cover 1 and being rotatable with said sleeve. Provided respectively in said flange and cover are perforations 15 and 16, those of the former being adapted to be carried into and out of registration with those of the latter for regulating the volume of air admitted through the cover to the fuel contained in the receptacle or reservoir (not shown).

Having thus described my invention, what I claim as new, and desire to secure by Letters Patent, is—

1. The combination with the cover of an orchard heater, said cover having an opening therein, of an inner stack mounted on said cover about said opening and having 30 perforations therein, an outer perforated stack surrounding the inner stack to form an annular inclosed chamber between said stacks, an inwardly directed annular crimp formed in the outer stack to inclose said 35 annular chamber, and a perforated sleeve embracing one of said stacks and adapted for rotation with respect to the latter for carrying the perforations thereof into and out of registration with those of the stack 40 which it embraces.

2. The combination with the cover of an orchard heater, said cover having an opening therein, of an inner stack mounted on said cover about said opening and having 45 perforations therein, an outer perforated stack associated with said inner stack and shaped to form an annular chamber between said stacks, and a perforated sleeve embracing one of said stacks and adapted for rotation with respect to the latter for carrying 50 the perforations thereof into and out of registration with those of the stack which it embraces, said cover having a series of perforations therein encircling the opening 55 thereof, and said sleeve having at its lower end an annular flange provided with perforations which are adapted, upon rotation of said sleeve, to be carried into and out of registration with said series of perforations 60 provided in the cover.

3. The combination with the cover of an orchard heater, said cover having an opening therein, of an inner stack mounted on said cover about said opening and having

perforations therein, a perforated sleeve embracing said stack and rotatable with respect thereto for carrying its perforations into and out of registration with those of said stack, and an outer stack having portions disposed in embracing engagement with said sleeve and adapted to rotate with the latter, said outer stack being formed to provide an annular chamber between it and said sleeve and having passages opening therethrough into said chamber. 75

4. The combination with the cover of an orchard heater, said cover having an opening therein, of an inner stack mounted on said cover about said opening and having perforations therein, a perforated sleeve embracing said stack and rotatable with respect thereto for carrying its perforations into and out of registration with those of said stack, and an outer stack having portions in embracing engagement with said sleeve and adapted to rotate with the latter, said outer stack being formed to provide an annular chamber between it and said sleeve and having passages opening therethrough into said chamber, and an annular 80 flange formed on the lower end of said sleeve and resting on said cover about the opening in the latter, said cover and said flange having perforations which are adapted to register when said sleeve is rotated to 85 certain positions.

5. The combination with the cover of an orchard heater, said cover having an opening therein, of an inner stack mounted on said cover about said opening and having 100 perforations therein, a perforated sleeve embracing said stack and rotatable with respect thereto for carrying its perforations into and out of registration with those of said stack, and an outer tapered stack having 105 its smaller end disposed in embracing engagement with said sleeve near the lower end of the latter, said outer stack having an inwardly directed crimp therein which embracingly engages said sleeve near the 110 upper end of the latter whereby is formed an inclosed chamber intermediate said outer stack and said sleeve, and means admitting air to said chamber.

6. The combination with the cover of an 115 orchard heater, said cover having an opening therein, of an inner stack mounted on said cover about said opening and having perforations therein, an outer perforated stack associated with said inner stack to 120 form an annular chamber between said stacks, and an inwardly directed annular crimp formed in the outer stack to inclose said annular chamber.

7. The combination with the cover of an 125 orchard heater, said cover having an opening therein, of an inner upwardly tapered stack mounted on said cover about said

opening and having perforations therein, an outer perforated downwardly tapered stack surrounding the inner stack to form an annular chamber between said stacks, and an inwardly directed annular crimp formed in the outer stack at a point adjacent to the upper end of the inner stack to inclose said annular chamber.

In testimony whereof, I affix my signature in presence of two subscribing witnesses.

JAMES L. HAMILTON.
